UNITED STATES PATENT OFFICE.

ALBERT KRAUTH, OF HAMILTON, OHIO.

MANIFOLDING DEVICE.

1,212,509.

Specification of Letters Patent. Patented Jan. 16, 1917.

Application filed February 27, 1915. Serial No. 10,917.

To all whom it may concern:

Be it known that I, ALBERT KRAUTH, a citizen of the United States, and residing at Hamilton, in the county of Butler and State of Ohio, have invented new and useful Improvements in Manifolding Devices, of which the following specification is a full disclosure.

My invention relates to an improvement in autographic registers or manifolding devices, and in particular to a type known to the trade as pull-out machines, from which measured sheet lengths of paper are withdrawn. The paper at one end of the machine is manually grasped and pulled forwardly until the end of a measured length of paper registers with the tearing edge of a tearing-blade. The paper is then transversely severed. This, without means for arresting the paper, requires careful observation and gradual pull toward the end of the measured length, requiring skill for satisfactory and speedy performances.

The invention herein avoids any delicacy of operation, and an object, therefore, is to provide means movable transversely to the plane of the paper to automatically engage through an aperture or apertures which are at measured distances in the paper to intercept its progress over the writing table as the apertures come in registry with the intercepting means.

A tearing blade bridges over the forward end of the writing table for severing the withdrawn portion of the paper, and which is hinged to swing upwardly for access to the end of the paper upon the table. The intercepting means, as yielding detents, are adapted, for releasing the paper, to be detracted and moved below the table plane, by means connecting with said tearing blade, so that the intercepting means are controlled with the control of the tearing blade, minimizing the manual operations necessary to a paper withdrawal.

Another object of my invention is to provide a series of paper feeding arresting devices progressively stationed, adapted to engage through a plural number of apertures spaced longitudinally of the paper for intercepting the paper in the withdrawal of the sheet and to retain a sheet length against longitudinal displacement within the machine.

55 Other features and advantages of the in-

vention, will be more fully disclosed in the description of the accompanying drawings, forming a part of this specification, in which like characters of reference denote corresponding parts throughout the several views, of which:

Figure 1 is a top plan view of a manifolding machine illustrating the forward end of the machine embodying my invention the cover being broken away. Fig. 2 is a detailed side elevation of a portion of the forward upper end of the machine with a part broken away, shown in Fig. 1. Fig. 3 is a section taken on line 3—3, Fig. 1. Fig. 4 is an end elevation of the forward upper end 70 of the machine which embodies my invention with parts thereof shown in section and others shown broken to show hidden parts. Fig. 5 is a top plan view, partly mutilated, of a portion of a manifolding device of a modified form of the invention. Fig. 6 is a section on line 6—6, Fig. 5. Fig. 7 is a top plan view of a modified form from that shown in Fig. 5. Fig. 8 is a section on line 8—8, Fig. 7 with the section not on a true 80 line for showing the rear support for the rearwardly extending actuator link in elevation.

The machine, in general, represents a well known type of construction, comprising a pair 85 of side frames 1, 2, secured upon a base 3 between which the supply webs of paper 4 are suitably mounted, the number depending upon the size of machine employed for serving the varicus purposes and demands required. The side frames may be of sectional 90 form and arranged in units, one mounted upon another for convenient access to the interior of the casing. The paper strips from the webs are respectively fed over 95 rollers 5 to guide the same across a writing-table 6 supported between the side frames, at the upper portion thereof, and marginally inclosed by a margin frame 7, which may be hingedly mounted to one of the side frames. 100 As the paper advances toward the forward end of the machine it passes beneath a cross-bar 8, secured to the side frames. A tension-blade 9 presses against the cross-bar to grip the paper fed between the blade and the 105 cross-bar to prevent any reverse movement thereof; the writing-table being suitably notched at such portion of the machine for tension blade clearance. Above the writing-table, at the forward end of the machine, a 110

tearing-blade 10 is provided, pivoted to the side frames and held under tension against the writing-table. The tearing-blade has a pair of arms 11 bridging the side frames and secured to the rock shaft 12, journaled in the side frames, with one of its arms provided with a handle extension 13 reaching rearwardly.

Beneath the writing-table 6 and toward the forward portion thereof, a pair of resilient blades 14, 14, are secured in parallelism, their free ends each provided with a pin 15, each pin projecting through an aperture in the writing-table and normally 15 through an aperture in the cross-bar 8. These pins are in alignment with the perforations in the paper, so as to engage with the perforations when they are moved into registry with the pins, and thereby 20 intercept the paper to arrest its progress. During the withdrawal of the paper the pins are yieldingly urged against the lower face of the paper and snap into a paper arresting position as soon as the set of apertures comes 25 into registry therewith. The pins in Figs. 1 and 3 are shown beneath the tearing-blade and slightly in rear of its tearing edge, which provides for a severance of the paper slightly beyond the perforations, leaving 30 the same intact so that the paper may be locked against reverse motion, which is of advantage when a manifold number of sheets are simultaneously withdrawn, insuring the text registry of the several sheets 35 with which the machine is threaded.

Prematurely to a withdrawal of the sheets, it is necessary to release the pin engagement with the paper, as well as to raise the cutting edge of the tearing-blade from the table; and to reduce the number of manipulations required for the paper release, the paper feed arresting devices and tearing-blade are connected, so that in a movement of the one, both will move coördinately to 45 a position of paper release. The resilient blades 14 are each provided with a slotted lug 16 projected downwardly therefrom, each respectively adapted to be engaged through its slot by arms 17 fixed to the rock 50 shaft 18 journaled in brackets 19 secured to the under side of the writing-table 6. The end of the rock shaft 18 has a pinion 20 fixed thereto, in mesh with the rack sector 21, fixed to the rock shaft 12, to which the 55 tearing-blade is secured. Thus, when the tearing-blade is rocked upwardly to bring its cutting edge above the writing-table sufficiently for convenient grasping of the end of the paper the pin members 14 will be co-ordinately moved so as to bring the ends of their pins below the plane of the writing-table, releasing the paper.

A spring 12^a, coiled around the rock shaft 12 having one end fixed to the shaft and its 60 other end to the side frame 2 (see Fig. 4)

provides the proper tension for rocking the shaft in a reverse direction, to automatically return the tearing blade and parts connecting with the shaft to their normal position after the operator releases his hold, or depressing pressure, upon the handle 13.

With a slight withdrawal of the paper the registry between the apertures in the paper and the pins or detents is disturbed so that the tearing blade may be lowered to its normal position which frees the pins permitting them to press against the under surface of the paper, as the paper is being withdrawn and to snap through the succeeding set of apertures when brought into registry. The tearing blade in its normal position has its cutting edge elevated to be free from contact with the table or paper and the paper thus can be freely withdrawn after it is released from the pins.

In loading a machine, it is desirable to sustain the arresting devices, tearing-blade and tension-blade 9 in a paper releasing position, and this is accomplished by the following devices:—

24 represents a rock shaft journaled in the side frames to which a handle rod 25 is fixed and projects forwardly therefrom, reaching to a position accessible from the exterior of the register. The shank portion of the rod 25 presses against the cam lug 26 projecting from one of the side frames to hold the rod after it has been swung to rock the shaft 24 and restrain said shaft from oscillating reversely under the tension of the 90 spring 27 connected with the rock shaft and side frame. The rock shaft at one of its ends has a cam 28 fixed thereon, engaging with a lug 29 formed on one of the arms of the tearing-blade, see Fig. 2, for swinging 95 the tearing-blade when the shaft 24 is rocked. The shaft 24 has an arm 30 projecting therefrom, adapted to engage with the tension-blade 9 to move it to a paper releasing position simultaneously with the movement of 100 the rock shaft 24, and as the tearing-blade shaft 12 engages with the paper arresting devices, they likewise will be moved to a 105 paper releasing position.

Now referring to Figs. 5 and 6, it will be observed that the pin-carrying resilient blades 14, 14, are of an extended form reaching rearwardly beyond the point at which they are fixed to the writing-table 6, providing the resilient pin carrying extensions 14', 14', each having a pin 15' fixed thereto at its free end, and passing through respective apertures in the writing-table and margin-frame 7. These pins pass through registering apertures in the paper at the 110 rear end which together with the forward pins, retain the intervening sheet length, or superimposed sheets, rigidly against displacement, and maintain the registry of the sheets upon the writing table. The rear 115

series of pins intersects the paper simultaneously with the forward series and to controlled coördinately with the movements of the tearing-blade 10. The mechanism for controlling the forward set of pins and that of the tearing-blade is substantially as that heretofore described, as illustrated in Figs. 1 to 4 inclusive, and which need not be here reiterated. The rock-shaft, however, is provided with a pin 32, projecting therefrom and engaging an aperture 33 in the connecting link 34. The link 34 is slidably supported upon the underside of the writing-table 6 and intermediate of the pin carrying blades. The rearward end of the link is notched to receive the headed pin secured to the under side of the writing-table, and is further provided with a rigidly secured cross plate 35. This cross plate 35, toward the ends of its forward edge is provided with the upwardly turned cam lips 36, 36, respectively engaging with the downwardly turned ends of the pin carrying blade extension 14', 14'. Thus, when the rock shaft 18 is moved in a direction for pin release, the pin 32 will move an appropriate direction, in this instance, forwardly, to flex the blades, and bring the pins downward below a paper intersecting plane; a reverse movement normalizes the parts. In this modified arrangement, the pins are located more toward a medial line with the paper, wherein in the link 34 can be efficiently located intermediate the pin carrying blades.

In Figs. 7 and 8, the pin carrying blades are separated to a greater degree and are located toward the margins of the paper. In such instance, it may be preferable to provide each pin carrying blade or yielding pin support with its individual control connection, each comprising a connecting link 34', pivotally connected to an arm 37 fixed upon the shaft 12. The free end of the link is bent to provide an angular shoulder 38, which engages with a yoke arm 39 transversely secured to the blade extension 14'. The method of control is substantially the same as those of the previously described structures, except that motion for the links 34' is taken from the tearing-blade shaft 12 instead of through the rock-shaft 18.

Having thus described my invention, I claim as new and desire to secure by Letters Patent of the United States:

1. In a manifolding machine, a pair of side frames, a writing-table interveningly connected to said side frames over which a strip of paper having apertures spaced longitudinally is drawn, a member yieldingly urged toward a face of said paper adapted to engage through a registering aperture in the paper to intercept its progress, a rocking tearing-blade across which a withdrawn length of paper is severed from the strip, and means connecting said tear-

ing-blade and member for moving both to a position of release coördinately with the movement of one.

2. In a manifolding machine, a frame structure having a writing-table as a portion thereof, over which a strip of paper is drawn, the paper provided with longitudinally spaced apertures, a tearing-blade hingedly mounted upon the frame structure having its cutting edge spanning the writing-table and across which the paper is transversely severed, and means adapted to intersect the paper through a registering aperture to arrest its progress controllably connected with said tearing-blade for moving both to a position of release coördinately with the movement of one.

3. In a manifolding machine, a frame structure having a writing-table as a portion thereof, over which a strip of paper is drawn, the paper provided with measured spaced apertures longitudinally therewith, a plurality of yielding means mounted with respect to the writing table and in a spaced relation longitudinally of the table, the spacing corresponding to the aperture spacing longitudinal of the paper to intersect the paper through the relative registering apertures to retain an intervening area of paper against movement upon said writing table, and means for moving said means to positions of paper release.

4. In a manifolding machine, a frame structure, a writing table supported thereby over which a strip of paper is drawn, the paper provided with definitely spaced apertures longitudinally therewith, a movable tearing-blade having its cutting edge extended transversely across the writing-table and at one end thereof, means movable to intersect the paper through a plurality of registering apertures with an area of paper upon the writing-table longitudinally intervening and arrested against movement, and coupling devices connecting said tearing-blade and said means for simultaneously controlling both with the control of one.

5. A device of the nature disclosed combining a frame, a writing-table over which a strip of paper is drawn, the strip having apertures predeterminedly spaced longitudinally, a plurality of members mounted to engage through apertures in the table and said members relatively spaced longitudinally of the table, the spacing corresponding to the paper aperture spacing and each member yieldingly urged toward a face of said paper to engage through registering apertures in the paper confining a portion intervening said yielding members upon the table and means for simultaneously retracting said members for paper disengagement.

6. A device of the nature disclosed combining a frame, a writing-table over which a strip of paper is drawn, the strip having

5 apertures predeterminedly spaced longitudinally, a plurality of members, each yieldingly urged toward a face of said paper and relatively spaced coördinately with said 10 paper aperture spacing, adapted to engage through respective registering apertures to retain the intervening area of paper, a movable tearing-blade having its cutting edge extended across said writing-table and connecting with said members for moving the same to positions of paper release coördinately with a movement of said tearing blade.

7. A device of the nature disclosed combining a frame, a writing-table over which a strip of paper is drawn, the strip having apertures predeterminedly spaced longitudinally, a plurality of members, each yieldingly urged toward a face of said paper and relatively spaced coördinately with said 20 paper aperture spacing, adapted to engage through respective registering apertures to retain the intervening area of paper, a movable tearing-blade having its cutting edge extended across said writing-table and connecting with said members for moving the same to positions of paper release coördinately with a movement of said tearing-blade, and means for moving and retaining 30 said tearing-blade member in non-functioning positions.

8. In a manifolding machine, a pair of side frames, a writing-table secured between

35 said side frames over which a strip of paper is drawn, the strip having apertures predeterminedly spaced longitudinally, a flexible member intermediately secured beneath the writing-table to provide opposite free ends, each provided with pins projecting through 40 respective apertures in said writing-table and in coördinate paper aperture spacing to respectively engage through the registering apertures to retain the paper upon said writing-table.

9. In a manifolding machine, a pair of 45 side frames, a writing-table secured between said side frames over which a strip of paper is drawn, the strip having apertures predeterminedly spaced longitudinally, a flexible member intermediately secured beneath the 50 writing-table to provide opposite free ends, each provided with pins projecting through respective apertures in said writing-table and in coördinate paper aperture spacing to respectively engage through the registering 55 apertures to retain the paper upon said writing-table, and means for simultaneously moving said pins to positions of paper release.

In witness whereof, I hereunto subscribe 30 my name, as attested by the two subscribing witnesses.

ALBERT KRAUTH.
